ATTORNEYS.

UNITED STATES PATENT OFFICE.

WILLIAM WALTER, OF PHILADELPHIA, PENNSYLVANIA.

UNDERGROUND CONDUIT.

SPECIFICATION forming part of Letters Patent No. 400,810, dated April 2, 1889.

Application filed March 22, 1888, Serial No. 268,127. (No model.)

To all whom it may concern:

Be it known that I, WILLIAM WALTER, a citizen of the United States, residing in the city and county of Philadelphia, State of Pennsylvania, have invented a new and useful Improvement in Underground Conduits, which improvement is fully set forth in the following specification and accompanying drawings.

10 My invention relates to improvements in underground conduits.

In Letters Patent granted to me April 28, 1885, No. 316,700, and July 28, 1885, No. 323,241, respectively, are shown, described, and 15 claimed underground conduits for electric wires, cables, heating or steam pipes, sewer-pipes, &c.; and the object of the present invention is to produce an underground conduit which will make provision for the above, and 20 also for an underground railway, combining the features of the patents with the railway system.

A further object of the invention is to combine all the desired features in a conduit of 25 the character named, whereby each can perform its function in a perfect and thorough manner, and which will permit ready access to all the parts of the conduit for the purpose of repair, inspection, and the like.

30 To attain these objects, my invention consists of the combination of parts as herein-after set forth and claimed.

In the accompanying drawing, which forms a part of this specification, the figure is a view, 35 partly in section and partly in perspective, of an underground conduit embodying my invention.

Referring to the drawing, the numeral 1 designates the trench or excavation, of suitable proportions for the desired purpose.

40 2 designates the floor or base of the trench, having passage-ways or gutters 3 at each side.

The frame-work of the conduit consists of 45 sections each composed of main uprights with perforated plates secured thereto, side and curved central cross-bars, short uprights, and top curved or segmental bars. The standards or uprights 4 project upward from the base, and at their upper ends are connected by the 50 side pieces, 5, and curved central piece, 6. The curved or segmental bar 7 is supported on the

side pieces and center piece by means of short pieces or uprights 8 of varying heights, the whole forming what may be termed a "truss."

The standards are arranged to form three 55 spans or arches—a wide central and two side arches—and the standards are placed at suitable distances apart throughout the length of the conduit. Secured on the standards in the side arches are plates 9, having openings or 60 perforations 10 therein to allow the passage of electric wires, and opposite to the plates 9 are plates 11, having openings 12 therein to allow pipes to pass therethrough to be used for gas, air, steam, hot air, and like purposes.

65 Floorings 13 are supported in the side arches by the standards to permit access to the wires and pipes for purpose of inspection or repairs, and pipes may also rest on the said floorings to be used for gas, air, steam, hot air, 70 or like purpose.

On the base or floor of the trench, in the center thereof, is laid a track, 14, such as are used to run cars on, and in the center of the track is situated the pulley 15, over which the 75 cable passes, of well-known construction.

16 designates sewer or drain pipes placed, preferably, to one side of the passage-ways or gutters, and being connected therewith by means of pipes 17, and also connected with 80 the street and floors supported in the side arches by means of pipes 18, whereby the sewer drains the street as well as the gutters and floors in the underground conduit.

To permit access to the sewer-pipe from the 85 passage-ways for the purpose of repairing the sewer, I provide man-holes 19 at intervals along the length of the passage-ways.

20 designates a ventilating-fan carried on a shaft journaled in the curved central piece, 90 6, of the frame-work, and having a pulley around which passes a band driven by cable-pulleys or other means.

The street-surface 21, which may be composed of concrete or other suitable material, 95 is supported upon a roofing of the truss, which roofing may be of properly-prepared timbers supported on the bars 7; or the surface material may be directly supported by the said bars 7. In the said street-surface and on the 100 bars 7 are timbers on which the tracks 22 are laid, and the cable 23 thereunder passing

over pulleys 24, journaled in the truss of the frame-work of the conduit.

25 designates the pavement or sidewalk, from which communication to the underground railway is had by means of the underground passage 26, which leads by means of stairways from the sidewalk to the underground conduit. These underground passages will be provided at intervals along the 10 line with stations or waiting-rooms at each of such passages.

Supported by the truss of the frame-work are pipes 27, to be used for gas, steam, air, or other suitable purposes.

15 From the foregoing description and drawing it will be seen that I provide an underground conduit which combines all the desired features in a perfect and simple manner, and which can be constructed at a cost comparatively low.

Having thus described my invention, what I claim as new, and desire to secure by Letters Patent, is—

1. In an underground conduit, a frame consisting of sections, each section having uprights with side and central connecting-bars,

and top segmental bars sustained on said side and central bars by short uprights, said frame being adapted to sustain on said top segmental bars the ground surface, and on its 30 uprights suitable pipes, substantially as described.

2. An underground conduit consisting of sections having uprights and cross-bars, as described, the flooring 13, connecting said 35 sections, a base with side gutters, sewers under said side gutters, and separate pipes leading from the street-surface and side gutters to said sewers, substantially as and for the purpose set forth.

3. In an underground conduit, the combination of sections having top curved or segmental bars, 7, and short uprights 8, supporting said bars, timbers resting on said bars and having the tracks 22 secured thereto, rollers 45 24, journaled in uprights 8, and the cable 23, substantially as and for the purpose set forth.

WILLIAM WALTER.
